UNITED STATES PATENT OFFICE.

JOSEFINE VETTER, OF MOUNT VERNON, NEW YORK.

CROCHETING-FORK.

SPECIFICATION forming part of Letters Patent No. 297,881, dated April 29, 1884.

Application filed October 10, 1883. (No model.)

To all whom it may concern:

Be it known that I, JOSEFINE VETTER, a subject of the Emperor of Austria, residing at Mount Vernon, in the county of Westchester and State of New York, have invented new and useful Improvements in Crocheting-Forks, of which the following is a specification.

This invention relates to forks used in 10 crotchetting or knitting what is known as "fork-work," such as lace "insertions," &c.; and it consists in a fork the prongs of which may be adjusted so that the distance between them may be changed as desired.

15 In the accompanying drawings, Figure 1 is a perspective view of my invention. Fig. 2 is a section of the same in the line x x , Fig. 1. Fig. 3 is a modification.

Similar letters indicate corresponding parts. 20 In the drawings, the letter A designates the rigid prong of the fork, from the lower end of which projects at right angles the leg B. C is the movable prong, which is provided at or

near its lower edge with an opening, a, which fits the leg B and slides over the same. The 25 set-screw D serves to hold the movable prong C in the desired position. The modification shown in Fig. 3 shows both prongs movable on a straight rod. Formerly in crocheting this work it was necessary to have a different-sized 30 fork for each width of lace; but it is obvious that my invention makes but one for necessary for all widths.

What I claim as new is—

A crocheting or knitting fork the prongs 35 of which are adjustable, so that the distance between them may be changed as desired, substantially as and for the purpose described.

In testimony whereof I have hereunto set my hand and seal in the presence of two sub- 40 scribing witnesses.

JOSEFINE VETTER. [L. S.]
